[57] **ABSTRACT**

The low temperature liquid storage tank having crack-detecting means of the present invention is provided with at least a heat insulating layer and at least an impermeable layer applied to the inner wall of the tank shell in laminated relationship with each other. A plurality of hermetically sealed sources of radio-isotope are secured to the inner surface of the tank shell so that any crack in the impermeable layer, if such is generated, can be detected by detecting leakage of radiation from the sources through such a crack by a dosimeter.

LOW TEMPERATURE LIQUID STORAGE TANK HAVING CRACK-DETECTING MEANS

BACKGROUND OF THE INVENTION

The present invention relates to a low temperature liquid storage tank having crack-detecting means and, more particularly, to a low temperature liquid storage of the internal heat insulating type having crack-detecting means wherein at least a heat insulating layer and at least an impermeable layer are laminated on the inner wall of the tank shell.

Heretofore, in a low temperature liquid storage tank of the internal heat insulating type, it has been extremely difficult to discover cracks generated in the impermeable layer provided on the inner wall of the tank shell. In case an impermeable layer of a thin metallic sheet is provided at the innermost side of the internal heat insulating layer, a clearance is formed between the impermeable layer and the heat insulating layer into which clearance a gas such as ammonia gas is introduced, and detecting liquid is applied along the seam of the metallic thin sheet of the impermeable layer so that any crack in the seam, if such is generated, can be detected by the detecting liquid.

However, the use of a thin metallic sheet as the impermeable layer is economically disadvantageous, and, in case a clearance is formed between the thin metallic sheet and the heat insulating layer, the thin metallic layer might be subjected to breakage by the movement of the low temperature liquid in the tank caused by the rolling of the ship. To avoid such a defect, it has been proposed to provide in place of the metallic thin sheet an impermeable layer comprised of a synthetic resin layer and a metallic foil applied closely in contact with the surface of the heat insulating layer or to provide a secondary impermeable layer in the interior of the heat insulating layer. However, problems arise in such an impermeable layer that detection of cracks (including pinholes) is extremely difficult.

SUMMARY OF THE INVENTION

The present invention aims at avoiding the difficulties in the prior art low temperature liquid storage tank.

Therefore, the object of the present invention is to provide a novel and useful low temperature liquid storage tank having crack-detecting means in which detection of cracks possibly generated in the impermeable layer of the tank can be easily and exactly effected by the provision of sources of radioactive element on the inner wall of the tank shell.

The low temperature liquid storage tank having crack-detecting means in accordance with the present invention comprises at least a heat insulating layer and at least an impermeable layer applied to the inner wall of the tank shell in laminated relationship with each other, the tank being characterized in that a plurality of hermetically sealed sources of radioisotope are secured to the inner surface of the tank shell in spaced relationship from each other.

By the low temperature liquid storage tank having crack-detecting means of the present invention described above, since a plurality of hermetically sealed sources of radioisotope are provided in the distributed condition along the inner surface of the tank shell, any crack which might be generated in the impermeable

layer can be exactly detected by measuring the emissivity of the radioisotope from within the tank.

As described above, the inspection of cracks in each of the impermeable layers in the inside of the tank shell of low temperature liquid storage tank of the internal heat insulating type can be quickly and accurately carried out thereby greatly improving the security of the tank.

BRIEF DESCRIPTION OF THE DRAWINGS

FIG. 1 is a schematic cross-sectional view showing the hull of a ship in which a low temperature liquefied gas storage tank having crack-detecting means in accordance with the present invention is incorporated;

FIG. 2 is a fragmentary cross-sectional view in enlarged scale showing in detail a portion of the low temperature liquefied gas storage tank of FIG. 1;

FIG. 3 is a diagram showing the results of measurement of the emissivity of radiation given in relation to the conditions shown in FIG. 2; and

FIG. 4 is a fragmentary cross-sectional view showing in more detail the construction of the source of radioisotope shown in circle A₀ in FIG. 2.

DETAILED DESCRIPTION OF PREFERRED EMBODIMENT

Referring to FIG. 1, a primary impermeable layer 3 made of a low temperature resistant material is provided on the inside of the tank shell 1 forming the hull with the interposition of a heat insulating layer 2 of a material such as foamed resin. Ballast tanks B are provided at both the ship's sides and the ship's bottom. The space L is used to receive the low temperature liquid for storage thereof.

In FIG. 2, a secondary impermeable layer 4 is shown as being provided in the interior of the heat insulating layer 2 arranged between the tank shell 1 and the innermost primary impermeable layer 3.

In accordance with the characteristic feature of the present invention, a plurality of hermetically sealed sources 5 of radioisotope (only one of which is shown in FIG. 2) are secured to the inner surface of the tank shell 1 in spaced relationship from each other.

The heat insulating layer 2 is divided into a primary heat insulating layer 2a and a secondary heat insulating layer 2b by the secondary impermeable layer 4. As to the material for forming these heat insulating layers 2a, 2b, a material having a superior heat insulating property such as hard polyurethane foam, polystyrene foam and polyethylene foam may be employed.

As to the material for forming the tank shell 1, an ordinary steel for ship construction may be used which is not noted for having a low temperature resistant property. However, as to the material for forming the primary impermeable layer 3 and the secondary impermeable layer 4, a composite low temperature resistant material such as a material sold by the Tradename "Aluminilar" having metallic foils of a high malleability and a low gas permeability such as aluminum foils laminated with polyester resin and a composite material having glass fibers or carbon fibers combined with polyurethane resin, epoxy resin, silicone resin of polytetrafluoroethylene, tetrafluoroethylene copolymer must be used.

Referring to FIG. 4, the hermetically sealed source 5 of radioisotope is secured to the inner surface of the tank shell 1 by means of bonding agent 6 and received in the recess of the second heat insulating layer 2b. The

sealed container 5a made of lead of the source 5 is formed with a window 5b opening toward the interior of the tank. A capsule 5c is housed in the container 5a and a predetermined quantity of radioisotope 5d (cobalt 60, for example) is hermetically housed in the capsule 5c.

Thus, when the emissivity of radiation from the source 5 is measured from within the tank at the periodical inspection by a suitable instrument such as a dosimeter, results shown in FIG. 3 are obtained, if cracks CI, CII exist in the primary and secondary impermeable layers 3, 4 as shown in FIG. 2. By the inspection of the values of the peaks a, b in FIG. 3, it can be determined in which of the primary impermeable layer 3 and the secondary impermeable layer 4 the crack is generated, and then, by investigating the positions A, B on the primary impermeable layer 3, the positions of cracks CI, CII can be easily determined geometrically.

The inspection of cracks as described above can be effected during the construction of the tank. The crack inspection is to be carried out at the time the secondary impermeable layer 4 has been completed and at the time the primary impermeable layer 3 has been completed.

As to the radioisotope to be sealed in the source 5, cobalt 60 can be used most easily. In other words, the half life of cobalt 60 is 5.2 years, and, assuming that the depreciation period of the ship having the low temperature liquid storage tank described above is 20 years, the quantity of the radioisotope as the source 5 merely decreases to about one-sixteenth, and the quantity of 1 $\mu\mu\text{c}$ of radioisotope suffices for one source. Thus, the total quantity of the sources in a ship may be in the order of 1 $\text{m}\mu\text{c}$ thereby permitting the total quantity of 35 the sources to be limited to the degree capable of sufficiently insuring the security of the ship.

I claim:

1. Apparatus, comprising:

wall means defining a liquid storage tank; 40
at least one layer of heat insulating material laminated to and covering said wall means inside the tank; at least one layer of low temperature liquid-impermeable material laminated to and covering said one 45 layer of heat insulating material inside the tank; whereby the tank is adapted for storing low temperature liquid; a plurality of hermetically sealed sources of radioisotope secured on said wall means in spaced relationship to one another, each source including shielding providing window means oriented toward the inside of the tank, so that cracks in the at least one

5

low temperature liquid-impermeable layer may be detected from within the tank.

2. The apparatus of claim 1, wherein: the hermetically sealed sources of radioisotope are each constituted by a capsule of cobalt 60 encased in lead.

3. The apparatus of claim 1, comprising: a second layer of heat insulating material laminated to and covering the first-described layer of layer of low temperature liquid-impermeable material inside the tank; and a second layer of low temperature liquid-impermeable material laminated to and covering the second layer of heat insulating material inside the tank, whereby, the second layer of low temperature liquid-impermeable material functions as the primary layer of low temperature liquid-impermeable material and the first-described layer of low temperature liquid-impermeable material functions as a secondary layer of low temperature liquid-impermeable material.

4. The apparatus of claim 1, wherein: further including a tanker ship for transporting liquefied gas, said ship incorporating said liquid storage tank.

5. The apparatus of claim 1, wherein: said wall means is constituted by steel.

6. The apparatus of claim 1, wherein: the heat insulating material is constituted by rigid foamed plastic resin.

7. The apparatus of claim 6, wherein: the at least one layer of low temperature liquid-impermeable material is constituted by a composite aluminum foil laminated with polyester resin.

8. The apparatus of claim 6, wherein: the at least one layer of low temperature liquid-impermeable material is constituted by a composite of fiber reinforced polyurethane resin.

9. The apparatus of claim 6, wherein: the at least one layer of low temperature liquid-impermeable material is constituted by a composite of fiber-reinforced epoxy resin.

10. The apparatus of claim 6, wherein: the at least one layer of low temperature liquid-impermeable material is constituted by a composite of fiber-reinforced silicone resin.

11. The apparatus of claim 6, wherein: the at least one layer of low temperature liquid-impermeable material is constituted by a composite of fiber-reinforced polytetrafluoroethylene-tetrafluoroethylene copolymer.
